UNITED STATES PATENT OFFICE.

CHARLES J. HOLUB, OF COLUMBUS, OHIO, ASSIGNOR OF ONE-THIRD TO W. E. LAM-
NECK AND ONE-THIRD TO A. P. LAMNECK, BOTH OF COLUMBUS, OHIO.

MACHINE FOR FORMING SHEET-METAL ELBOWS.

Application filed May 16, 1923. Serial No. 639,411.

To all whom it may concern:

Be it known that I, CHARLES J. HOLUB, a citizen of the United States, and residing at Columbus, in the county of Franklin and State of Ohio, have invented a new and useful Improvement in Machines for Forming Sheet-Metal Elbows, of which the following specification is a full disclosure.

10 This invention relates to an improved machine for producing corrugated stove pipe elbows, in which the mechanism operates upon a sheet metal tube or pipe section to circumferentially corrugate the same, and as the corrugations are successively made the tube is progressively bent at the corrugations to the desired elbow angle.

15 The primary object of the invention is to provide a machine in which the mechanism is susceptible to high speed operation for increasing the capacity production of the machine, and which is automatic in its operation after manually loaded and started, and readily adjustable for making different 20 pipe sizes of elbows.

25 Other objects of the invention relate to improvements in the corrugating mechanism for geometrically forming each corrugation, and for expanding and compressing portions thereof in a bending operation for the production of an elbow, and to the bending mechanism for facility in loading and unloading of the machine.

30 Other objects and features relate to improvements in the mechanism for automatic control of the machine, in simplifying the construction of the machine, increasing its durability and avoiding complication heretofore experienced in machines of this class, 35 all of which will be more fully disclosed in the following description of the accompanying drawings forming a part of this specification, in which:

Figure 1 is a side elevation of the improved sheet metal elbow-forming or pipe corrugating machine.

Fig. 2 is a section on line 2—2, of Fig. 1.

Fig. 3 is an enlarged top plan view of the machine.

Fig. 4 is an enlarged section on line 4—4, of Fig. 2.

Fig. 5 is a section on line 5—5, of Fig. 4.

Fig. 13 is an end view thereof.

Fig. 14 is a side view.

Fig. 15 is a section on line 15—15, of Fig. 3.

Fig. 16 is a section on line 16—16, of Fig. 3.

Fig. 17 is a section on line 17—17, of Fig. 16.

Fig. 18 is a section on line 18—18, of Fig. 3.

The machine operates upon a piece of sheet metal bent to tubular or pipe form for corrugating the tubing circumferentially and then bending the tubing in the form 85 of an elbow at the corrugations, as illustrated in Fig. 8. The bending operation crimps the metal of each corrugation upon itself at a portion of the tube diameter and at an opposite portion expands the corrugation and to a degree for producing the desired angle bend of elbow, the bending operation being subsequent to each corrugating operation, so that the tubing is progressively corrugated and bent. After each corrugation is formed the sheet metal tube is advanced to the required degree for a second corrugation, and bent to a degree necessary for the formation of the desired angle 90 elbow. The bending of the tube into elbow form, as corrugated, is accomplished by means of a bending head or ring applied to and about one end of the tube, the head

cooperating with a pair of arms oscillating as a unit at an angle to the direction of the tube feed. The arms are arranged to swing apart, facilitating the manual insertion and withdrawal of the tube or elbow and attached head to and from the machine. For loading the machine the tube is engaged 100

105

110

Fig. 5 is a section on line 5—5, of Fig. 4.

Fig. 6 is a front end face view of the machine with the bed omitted and a portion broken away and shown in section for the

with the carriage, and the carriage is retreated as the tube is manually pushed into the machine. As the carriage reaches the limit of its retreat stroke the tube is automatically locked to the carriage and likewise automatically released as the carriage reaches its forward traversing limit. Likewise the transmission mechanism is automatically controlled through the movements of the carriage, so that the machine is started after the tube has been inserted and stops after the carriage has been moved to its forward limit. This greatly facilitates the operation of the machine to the relief of the operator.

Referring to the drawings, 1 indicates the bed of the machine, which may be of any conventional form, upon which a transmission mechanism and corrugating and bending mechanism is mounted. The transmission mechanism is mounted to occupy one end of the bed, and the corrugating and bending mechanism, the opposite end of the bed. The transmission mechanism comprises bearing brackets 2, 3, spaced apart and mounted upon the upper surface of the bed for journalling the power shaft 4, having a pulley 5 fixed thereon at one end. A spur pinion 6 is mounted upon and fixed to the shaft 4 and located between the bearings 2, 3, and in mesh with a larger diameter gear wheel 7 loosely mounted upon a countershaft 8 journalled in elevated bearings of the journal brackets 2, 3. The gear wheel 7 is connected to the shaft 8 by clutch mechanism manually and automatically controlled, the mechanism of which will be more fully hereafter described. The clutch for the gear wheel 7 may be of any type of construction, friction or toothed, the type of clutch employed specifically forming no part of the present invention, except only in so far as the control or operation thereof is pertinent to the control and operation of the corrugating and bending mechanism.

Arising vertically from the bed 1 and disposed adjacent to the bearing 3 is a vertical frame wall 9, providing bearings for a plurality of shafts disposed about the axis of the countershaft 8, which has an end bearing in said frame wall 9, as shown in section in Fig. 4. The shaft 8 is provided with a spur gear 10 keyed thereto and in mesh with four gears, 11, 12, 13 and 14, respectively fixed upon the ends of shafts 15, 16, 17 and 18, suitably disposed about the gear 10 to provide independent transmissions for each of a plurality of dies or plungers for circumferentially corrugating the tubing disposed between the dies.

The clutch for connecting gear 7 to the shaft 8 is disposed between gears 7 and 10 upon the shaft 8, and consists of the following parts: The shaft 8 has an enlarged diameter portion 19 as a hub and

which is longitudinally slotted to slidably receive a retractable latch bar 21, the latch bar being held in place within the groove by a collar 22 engaged about the periphery of the hub 19, the collar being slotted to provide an opening through which a lateral projection 23 of the latch bar projects. The latch bar is engaged by a spring 24 confined within the groove in the hub by a washer or plug 25 against which the spring 24 engages, the spring urging the latch bar outwardly for engagement with either of the pins 26-26, laterally projecting from the hub portion of the gear 7 for connecting the gear 7 with the shaft. The latch bar is actuated by a cam shoe 27 mounted upon an arm 28 pivotally connected to a bracket plate 29 fixed to the side of the bearing 3. The arm 28, at its forward end, is pivotally connected with a link 30, the link in turn being connected to an arm 31 engaged upon an actuator rod 32. The arm 28 has a branch extension 33 to which a spring 34 is connected, one end of the spring being engaged in the head of a screw 35 and in threaded engagement with the branch 33, the opposite end of the spring being engaged to the bracket plate 29, the spring urging the arm 28 upwardly to bring the shoe mounted thereon in engagement with the latch bar for disconnecting the gear 7 from the shaft 8.

The actuator rod 32 is engaged through and journalled in the wall 9, and extends forwardly, and its forward end engaged and journalled in a front frame wall 36, upon which the dies for corrugating the sheet metal tubing are mounted. The actuator rod is operated by a carriage, to which the sheet metal tube to be formed into an elbow, is connected, the carriage advancing in step degrees upon a mandrel between the front wall 36 and rear wall 9.

Carriage and carriage feeding mechanism.

The inner frame wall 9 is formed to include a pair of spaced lugs 37, between which the projecting ear 38 of the collar 39 is pivotally engaged, the collar providing a pivoted head for a horizontally extended mandrel or core 40. The mandrel 40 is situated in axial alignment substantially with the countershaft 8 and is adapted to have its outer end received within an opening in the outer or front frame wall 36. The collar 39 carries a set screw 41 engaged therethrough and into the rear frame wall 9 for rigidly securing the mandrel to the frame wall, the set screw also providing means for making the desired axial adjustment of the mandrel, vertically. It is also feasible to have the set screw merely engage the frame wall 9, which would permit the mandrel to swing vertically, for centering itself between and under the pressure of the opposingly

moving dies of the corrugating mechanism. In the manufacture of commercial sizes of stove pipe elbows, the mandrel is of a length which will permit it to flex sufficiently for centering between the dies, permitting the head of the mandrel to be rigidly secured to the frame wall 9.

The mandrel longitudinally is provided with a spline groove for receiving a slidable ratchet bar 42, having ratchet teeth 43 along its upper edge, the teeth of a pitch to obtain the desired degree of carriage step advance required for the proper corrugation spacing in a determined size of elbow to be produced. The ratchet bar is removable to be interchanged for other tooth gauge bars to change the degree of carriage step advance. The inner or rear end of the ratchet bar 42 connects to a spring pressed plunger 20 slidably supported in and engaged through the rear frame wall 9, for reciprocating the ratchet bar. The plunger consists of a yoke member 44 having cylindrical limbs 25 respectively engaged in and through bores in the frame wall 9. The limbs are connected by a cross plate 45 recessed into the mandrel head collar 39 and connected to a ratchet bar by a pair of tie bars 46 secured to the opposite sides of the cross plate 45 and depending therefrom and secured to the end of the ratchet bar (see Figs. 4 and 5). The plunger carries a roller 47 engaging a cam ring 48 fixed to the side of the gear wheel 10 upon the countershaft 8. The cam ring with each cycle of the gear 10 pushes the plunger and the ratchet bar 42 forwardly for producing a step advance of the carriage in timed relation to the operation of the corrugating dies. The carriage 40 advances intermittently for producing the corrugations singly in a serial order and for successively bending the tube at each previously formed corrugation while the tube is clenched between the dies. The sequences 45 are at a high rate of frequency enabling the rapid and efficient production of an elbow, and the tube is advanced in a direction of withdrawal from the machine, making it commodious to the operator for removing the finished elbow and inserting a second blank tube. The plunger and its roller are yieldably held into engagement with the cam ring by a pair of coil springs 49-49 respectively engaged upon rods 50-50 secured to and projecting from the rear frame wall 9, one end of said spring engaging against a cross bar 51 straddling and engaging the plunger plate 45 and slidably engaged upon the rods 50-50. Each rod 60 is provided with nuts threaded upon the end thereof engaging the opposite end of the spring, and by means of which the tension of the spring can be regulated.

A carriage 52 is arranged to slide longitudinally of and upon the mandrel and to

which one end of the sheet metal tube to be corrugated and formed into an elbow is connected. The carriage preferably is formed of a plurality of concentrically engaged or nested different diameter collars 70 secured together as a unit, and, as shown, comprises three collars, 53, 54 and 55, the inner one of which is provided with a spline groove to receive the ratchet bar 42, and diametrically opposite the groove carries a 75 key 56 engaged with a spline groove formed in the mandrel for the purpose of non-rotatively sustaining the carriage upon the mandrel. The inner collar 53 peripherally at one end is counterturned, while the second collar 54 is correspondingly counterturned externally and counterbored internally, the counterbore mating with the counterturned periphery of the inner collar to provide an annular recess 57 between the two collars 80 serving as a socket to receive the end of a length of pipe tubing for a determined pipe diameter. The third collar 55 is counterbored to mate with the counterturned periphery of the second collar, forming a 85 second pipe receiving recess or socket for a second size of pipe tube. Thus a plurality of different sizes of pipe can be socketed into the head, and said head may be enlarged upon to accommodate any number of 90 different sizes of pipe.

The pipe is locked within and to the carriage by a pin 58, and for the size of pipe tube length shown in the drawing, which is engaged with the socket formed between the 100 second and third collars 54, 55, the pin 58 is engaged transversely through an aperture in the collar 55 so as to be accessible by a cam or wedge bar or member 59 slideable within a longitudinal groove formed 105 within the bracket member 60 yoked to be secured about and to the outer collar 55 of the carriage. The wedge bar 59 is provided with a stem 61 extending therefrom and through an elongated slot 62 through the bracket member (see Fig. 7), by which the wedge bar 59 is actuated either manually or automatically at the opposite ends of the carriage traverse upon the mandrel. At the end of the carriage forward traverse 110 the stem engages a projecting finger 63 fixed to the rear side of the front wall 36, which with the carriage advance moves the wedge bar 59 rearwardly to release the lock pin 58, and is again depressed after the carriage 115 has been moved to its retreat or starting position, by engaging an arm 63^a (see Fig. 3) adjustably secured upon and projecting from a rod 63^b longitudinally parallel with the mandrel 40 and secured to and extending from the front side of the rear frame wall 9. Thus the wedge bar 59 as a slide bolt is operated at the forward and return limits of carriage traverse, the pin 58 automatically locking and alternately releasing 120

125

130

the pipe tube length from the carriage. The end of the slide or wedge bar 59 which engages the head end of the lock pin 58 is appropriately formed to wedge to force the pin inwardly, the pin biting into the pipe, and to hold the pin in such position until positively released. The collars 54 and 55 are provided with registering apertures 58^a through which a pin of appropriate length 10 is inserted for locking the pipe tube length within the socket 57 formed between the collars 53, 54. Providing separate pin apertures for each diameter of socket enables the pin to press the tube metal against the 15 surface of the socket so that there is no liability of puncturing the metal.

The carriage is intermittently traversed by a spring pressed pawl 60^a slidable in a slot in a bracket 52^b of the carriage and held 20 therein by the bracket 60^b for engaging with the teeth of the ratchet bar 42. The upper end of the pawl 60^a is engaged by a leaf spring 64 fixed to the bracket 52^a of the carriage. The pawl 60^a under a depressing tension 25 is urged upon the ratchet bar 42 for pawl engagement with a registering tooth shoulder of the ratchet bar. Thus as the ratchet bar 42 is moved in a forward stroke by the plunger engagement with the cam 30 surface of the cam ring 48 upon the gear wheel 10 the carriage 52 is traversed a definite step degree. Upon the return stroke of the ratchet bar 42 the pawl 60^a is expressed to ride over the teeth. The carriage 52 is 35 under retrograde pressure whereby the pawl 60^a is firmly retained against the shoulder of a ratchet bar tooth with which the pawl is in registration, preventing any overthrow of the carriage in a forward or feeding direction and automatically retreating the carriage when the pawl is moved positively out 40 of tooth engagement. This action of the carriage is accomplished by means of a weight 65 slidably sustained within a guide 45 hanger 65^a depending from the bed. (See Figs. 1 and 2.) The weight 65 is connected to a sprocket chain 66 extending upwardly and over an idle sprocket wheel 67 journaled within a bracket 68 fixed to the forward 50 side of the rear frame wall 9, and there connects to an eye screw threaded into the carriage. The weight at opposite sides is provided with straps 69—69 to which one end of the coil springs 70—70 respectively 55 are connected, the opposite end connecting with a cross bar 71 fixed to the cross rails of the guide hanger 65^a. The pawl 60^a is positively actuated for throwing the same out of engagement with 60 the ratchet bars releasing the carriage for its retreat stroke and automatically thrown into commission by the following instrumentalities:

A latch bolt 72 is mounted in a slot in 65 the bracket 60^b, slidably transversely to the

pawl 60^a and notched as at 73 for the reception of a pin 74 laterally projecting from the pawl 60^a (see Figs. 16 and 17). The notch provides an inclined surface for engaging beneath the pin 74 to elevate or 70 lower the pawl 60^a as the latch bolt is reciprocated. One end of the latch bolt 72 is engaged by an arm 76 fixed upon the axis of a hand lever 77 pivoted upon the ear 78 extending from the bracket 52^b on the carriage. The swing of the arm 76 is confined in outward direction by a pin 79 fixed to and extending from the bracket 52^a. As the hand lever 77 is manually actuated to swing the arm 76 forwardly toward the end of 80 the latch bolt 72, the latch bolt is slid in such direction wedging the pawl 60^a upwardly out of engagement with the ratchet bar 42 and sustained in said retreated position until the position of the latch bar is 85 reversed. The end of the latch bolt 72 opposite the latch shifting arm 76 has an L-extension 80 with a beveled end for engagement with the trip dog 91 adjustably secured upon the rod 63^b upon which the arm 63^a is mounted for actuating the slide bolt 59 for locking the pipe tube within and to the carriage. Thus if the pawl latch bolt 72 is positioned to sustain the pawl out of commission upon 90 the retreat traverse of the carriage, the inclined or beveled end 80 of the latch bolt is extended to engage with the stationary trip dog 91, which forces the latch bolt inwardly, permitting the pawl when its pin 74 is 100 in registry with the notch 73 to snap into engagement with the ratchet bar.

The carriage at the end of its strokes also controls the operation of the transmission gearing through the control of the clutch mechanism previously described, connecting transmission gear 7 with the shaft 8. The rotation of the shaft 8 is discontinued at the limit of the carriage forward traverse and remains at rest until the carriage has 110 been moved to its full retreat position for the size of the pipe tube operated upon. The carriage 52 remains in its full forward position until the carriage pawl 60^a has been manually released from the ratchet bar 42 and this usually after the pipe tube length has been engaged in the carriage so that the pipe tube is drawn into the machine with the carriage retreating traverse.

The bracket 60 upon the carriage has a reach or extension 93 adapted to engage with either of the trip dogs 94, 95, mounted upon the shifting rod 96 slidably supported at its opposite ends upon bracket lugs 97, 98, respectively fixed to and projecting in opposite directions from the front and rear frame walls 9 and 36. The trip dog 94 is rigidly connected to one end of the shifter bar or rod 96 and is provided with an upstanding stem 99 to furnish a hand grip for manually 112

actuating the shifter bar. The trip dog 94 is also provided with a rectangular tail extension 100 engaged with a notch in the bracket lug 98. The tail extension has a pin 101 engaged therethrough to prevent vertical displacement of the shifter bar. The bracket reach or extension 93 has a screw 102 engaged therethrough providing an adjustable abutment for engagement with the trip dog 94 to shift the shifter bar 96 forwardly as the carriage reaches the end of its forward traverse.

15 Clutch operation and transmission stop control.

In the retreat traverse of the carriage the bracket reach 93 engages the adjustable trip dog 95 appropriately set upon the shifter bar 96. The opposite or rear end of the shifter bar 96 has a trip dog 103 rigidly attached thereto and slidably engaged upon the bracket lug 97 as described for the forward end of the shifter bar in connection with the lug 98. The trip dog 103 has a tail extension 104 carrying a beveled shoe engaged with an inclined edge of an arm 105 fixed upon the rock shaft or rod 32, journalled in the frame walls 9 and 36, the rock shaft, as previously described, operating the cam shoe 27 of the transmission clutch mechanism. The arm 105 is provided with a hand grip stem 106 for manually actuating the rock shaft 32 from the side of the machine.

35 Corrugating mechanism.

The corrugating mechanism embodied in the machine (see Figs. 6, 9 and 10), comprises a plurality of dies arranged in diametrically opposing pairs upon the front frame wall 36 and reciprocating radially from the axis of the mandrel which is disposed centrally of the dies. Four dies are employed as segments combined to circumference the tube interposed between them to form a circumferential corrugation in the tube when the dies are moved toward the axis of the mandrel. The dies are operated simultaneously and cooperate with an anvil upon the end of the mandrel within the pipe tube. Each die has its individual actuating and transmission mechanism in driven connection with a common driving gear, namely gear 10, transmitting the gears 11, 12, 13 and 14, respectively fixed upon the ends of the shafts 15, 16, 17 and 18. These shafts extend longitudinally parallel with the mandrel and journalled in bearings in the front and rear frame walls 36 and 9. As the construction of the dies and the transmission and actuating mechanism of each are the duplicate of one another, the description thereof will be confined to the singular.

65 The outer ends of the shafts 15, 16, 17

and 18, are headed, the heads 108 journalled in bearing sockets in the front frame wall 36, and each head is provided with a crank pin 109. The crank pin is engaged into an eccentric bore of a bushing 110 having a portion of its periphery toothed for engagement with an adjusting lug whereby the bushing can be adjusted about the crank for pitman reach regulation. The bushing is engaged within a bore of a split end pitman or eccentric strap 111 and to which the bushing is frictionally clamped, the split portion of the pitman having opposing ears or lugs extended therefrom and parallel, through which an adjusting screw 112 is engaged for releasing and clamping the bushing frictionally rigid with the pitman. The pitman is situated to lie in a radial position with respect to the axis of the mandrel, and upon rotation of the shaft 85 the crank on the end thereof will impart radial reciprocating motion to the pitman and parts connected thereto.

The inner end of the pitman 111 terminates with a substantially circular or annular head 113 engaging into a socket of a slide 114 of dovetail formation for slidably engaging with and between the opposing guide plates 115-115, removably secured to the front face of the front frame wall 36. 00 The slide is provided with a removable plate 116 which retains the head 113 of the pitman within the socket of the slide. The socket provides sufficient clearance for pivotal action of the pitman within the socket. 100 The bushing is retained upon the crank pin against lateral displacement by a washer or disk 118 secured upon the end of the crank pin by a screw 119, threaded into the crank pin.

With a portion of the bushing periphery provided with gear teeth 120 and the pitman 111 with an aperture 121 as a socket for the axis of an adjusting key 122 adapted to be engaged into the aperture, and having a pinion 123 for working with the teeth of the bushing, the bushing may be rotatably adjusted. For an adjustment, the pitman clamping engagement with the bushing is sufficiently released to permit the bushing to 110 be rotated within the bore of the pitman. The adjustment regulates the reach of the slide and die fixed upon the slide with respect to the anvil mounted upon the end of the mandrel for obtaining the desired compression of metal between the die and anvil. 115

The slide at its end opposite the pitman connection is formed to provide a stock 124 which extends to overlap the guide plates 115-115, and its front face is recessed to 125 provide a semi-circular shoulder 125 for receiving a segmental corrugating die 126. The die constitutes a segmental plate removably secured to the stock of the slide, and presents a semi-circular edge 127, being of 130

- approximately 90° curvature. As shown in Fig. 6, the dies are arranged in opposing pairs with four dies embracing the circumference of the pipe tube to be corrugated.
- 5 The adjacent edges of the dies are formed to include lap joints 128 which serve to maintain proper registration and alignment of the dies as they move toward the axis of the anvil therebetween.
- 10 The outer end of the mandrel which projects through the opening in the front frame wall 36 is provided with a removable annular anvil consisting of a pair of disks 129, 130. The disk 129 is engaged and non-15 rotatively fixed upon the end of the mandrel which is counterturned to receive the disk; the second disk, 130, having an eccentric periphery, is fixed to the end of the mandrel by a screw 131 threaded into the 20 end of the mandrel and fixed to the disk 129 by pins 132. The lower half of the front face of the disk 130 is tapered to reduce its thickness to provide for a slight clearance for the metal compressed between 25 the anvil and dies when bending the tube to the form of an elbow, which is bent primarily about the die portion embracing the upper half of the pipe representing the crotch of the elbow. The eccentricity of 30 the disk 130 provides for a variation in the depth of the corrugations, being more shallow for the back portion of the elbow than for the crotch portion, to the formation of a more perfect elbow and bend. The corrugations at the crotch portion being compressed in the bending operation and the folds of the corrugations upon one another while the corrugations at the back of the 35 elbow are spread outwardly.
- 40 The disk 129 conforms substantially with the inner diameter of the pipe tube and the metal of the tube is bent about the front edges of the disk. The anvil is removable from the mandrel for interchanging with 45 different diameter anvils for making various pipe sizes of elbow.

Bending mechanism.

- One end of the pipe tube length is engaged 50 with the carriage and the opposite end has a removable cam ring 133 engaged thereon. The cam ring 133 has its bore counterbored and a steel bushing engaged and secured 55 therein, the counterboring providing an annular recess 134 open to one end of the ring as a socket for engaging the ring over the end of the pipe tube. The ring is of sufficient width to provide for a recess depth for 60 inserting the end of the pipe to a distance to bring the inner edge of the ring approximately at a point where the first corrugation is made and maintain a true cylindrical thimble end or elbow, and preventing the same from being distorted during the tube bending operations.

The tube bending ring or head 133 is provided with a pair of diametrically disposed cam lugs 135, each having a curved or cam surface 136 for engagement respectively with the arms 137—137, which swing inwardly, moving the bending head in forward and upward directions, expanding the corrugation from one side of the tube and compressing the same at an opposite side 70 as shown in Fig. 8. The bending operation 75 is at a timed period following a corrugating operation and when the pipe tube is gripped by the dies. The corrugations are therefore successively formed and the tube 80 successively bent into an elbow arc, the arc bearing a relation to the number of circumferential corrugations.

The arms 137—137 are mounted upon a rock shaft 138 to rock therewith and pivoted 85 each respectively on an axis 139 to swing laterally upon the rock shaft and relatively in opposing direction, adapting the arms to be spread apart for inserting the tube with the bending head 133 upon one end thereof 90 into the machine. The arms swing laterally 95 to clear the cam rings when pressed apart by the cam rings of the bending head when the tube is pushed into the machine. Each arm is provided with inclined guide 140 which is engaged by a respective cam ring 100 of the bending head, when the head is forced between the arms. The arms are under yielding restraint toward each other so as to be normally in position to engage the cam 105 rings of the bending head after the tube with the head attached thereto has been inserted within the machine. For this purpose a spring 141 at one end is fixed to the rock shaft through the angle iron 142, and the other end of the spring to the arm 110 through an angle iron 143.

A lever arm 144 is fixed to the rock shaft 138 between a pair of spaced brackets 145—145 fixed to the front end of the bed, which journal end supports the rock shaft. The 110 lever arm 144 extends downwardly and carries a bumper screw 146 which abuttingly engages a plunger bar 147 slidably supported in a bearing bracket 148 fixed to the bed 115 1 of the machine. (See Fig. 6.) The plunger bar is pivotally connected to the rock lever 149 disposed at an angle upwardly 120 engaged through an opening 150 in the top of the bed and pivoted to a bracket 151 fixed to the bed by bolts 152. The upper end 125 of the rock lever is provided with a roller 153 engaging the cam surface of a cam 154 fixed upon the shaft 18. The cam actuates the rock lever, imparting motion through the plunger bar 147, lever arm 144, rock shaft 138 to swing the arms 137—137 inwardly for a bending operation, the arms being retracted by a spring 155 having one end connected with the end of the lever arm 144 and its opposite end connecting with the 130

bed of the machine. The spring holds the arm in engagement with the plunger bar 147 and thereby serves to yieldingly hold the rock lever 149 and its roller 153 against the cam surface of the cam 154. The cam engaging end of the rock lever 149 in its retreat position engages against a stop screw 156.

In order to check the momentum of the rotating parts after the power has been cut off, suitable brake mechanism is employed, automatically controlled with the control of the clutch, connecting and disconnecting gear 7 from and to the countershaft 8. The shaft 16 for operating one of the corrugating dies is provided with a brake wheel 157 about which a brake yoke engages, consisting of a pair of brake levers 158—158, having a semi-circular portion rigidly connected together and engaged about the brake wheel, each carrying a lining shoe 159 adapted to bear upon the periphery of the brake wheel 157, and arm portions 160—160 yieldingly urged toward each other by a spring 161 engaged upon a stem 162 extending through one arm of one of the brake levers and fixed to the arm of the opposite brake lever. The brake levers are positively spread apart to release their braking engagement with the brake wheel by a cam member 163 fixed upon the rod 32 which actuates the clutch mechanism for the transmission gearing, the cam member 163 being disposed between the arm portion of the brake levers. Braking one of the shafts of the corrugating dies applies the brake at a location from which the momentum of the rotating parts is more effectively arrested with a minimum braking pressure as the gearing connecting shaft 16 with the countershaft 8 serve as back gears.

Mode of operation.

A piece of sheet metal of appropriate dimension is previously rolled into a tube for the desired elbow size, and with the bending head 133 engaged over one end thereof, is inserted into the machine between the corrugating dies, with the opposite end of the tube inserted and engaged into the carriage 52 which for loading is at limit of its foremost traverse upon the mandrel 40. The tube is engaged in the appropriate annular socket or recess in the side of the carriage and locked therein by the pin 58 after the carriage has been manually pushed rearwardly upon the mandrel to a starting position. The operator moving the carriage in a retreat direction by means of the tube through his hold upon the bending head. The carriage is disengaged from the ratchet bar, by manually throwing the hand lever 77 to slide the latch bolt 72 lifting the pawl 60 from engagement with the ratchet bar. The latch bolt remains in its pawl release

controlling position until actuated automatically when the carriage reaches the end of its retreat traverse. The weight 65 serves to move the carriage rearwardly, although force by the operator is required to move the carriage for actuating the various latch bolts and clutch tripping or controlling mechanisms. The tube is inserted into the machine, pushing the carriage rearward until the cam lugs 135 of the bending head are brought to the rear side of the bending arms 137 which swing apart as the head is forced therebetween. With the full insertion of the tube the pin or stem 61 of the latch bolt or wedge bar 59 is engaged by the stationary trip arm 63 for moving the latch bolt 59, forwardly depressing the pin 58 to grip the tube and lockingly secure the same to the carriage. At such time the latch bolt 72 is also slid in an appropriate direction by the stationary trip arm 91 for releasing the pawl for cooperation with the ratchet bar 42 upon the mandrel 40, connecting the carriage with the ratchet bar for intermittently feeding the carriage forward.

The carriage in its retreat motion and toward the end thereof actuates the clutch shifting bar 96 through the engagement of the arm or extension 93 of the carriage with the adjustable dog 95 upon the shifting bar, moving the bar rearwardly, which motion actuates or swings the arm 105 fixed upon the rock shaft or rod 32 through the connecting members 103 and 104 fixed to the shifting rod 96. The rocking motion of the rod 96 operates the clutch mechanism for connecting gear 7 to the countershaft 8 and the transmission remains in commission until the carriage has traveled forward the distance required to form the tube into an elbow.

When the clutch has been operated by the carriage for connecting the power to the countershaft, reciprocating movement will be imparted to all of the dies, which is continuous until the required number of corrugations has been formed in the tube. The eccentric gearing for reciprocating the dies produces an appropriate dwell to the motion of the dies at the ends of their reciprocating strokes, especially at the end of their forward or compression stroke, to grip the tube and provide a shoulder against which the corrugations are compressed at the crotch of the elbow in a bending operation. The timing of the ratchet bar actuation is such that the carriage and tube will be advanced a step degree after the dies have been withdrawn sufficiently to free the tube and before the dies again compressively engage the tube for forming a corrugation. The cam 48 is of such formation that it will move the ratchet bar forwardly carrying the carriage therewith and retaining the bar in such advanced position until the tube is

engaged by the dies to hold the same against retrograde motion, while the ratchet bar retreats sufficiently for a successive tooth engagement of the pawl, or the action of the 5 ratchet bar may be at such a rate due to the formation of the cam which will effect a slight overthrow to the carriage for obtaining a tooth advance of the pawl with the ratchet bar return stroke of the ratchet bar 10 before the dies with the compression engage the tube. The weight 65 holds the pawl against the shoulder of the teeth of the ratchet bar, although the tube and carriage can move forward under the drawing action 15 of the metal during the process of forming a corrugation.

The corrugating dies, each being reciprocated by its own eccentric gear, can be independently adjusted and timed for producing 20 a corrugation varying in channel depth circumferentially of the tube, most appropriate for the bending operation, without shearing or tearing the metal in either the corrugating or bending operation and produce a high 25 quality product.

With the employment of four dies a very uniform compression is obtained circumferentially about the tube, avoiding twisting of the tube which would be detrimental to the 30 angle of the elbow and destroy its axial alignment from one end to the other.

At an appropriately timed interval after the completion of a corrugation operation the bending arms move forwardly, causing 35 the bending head to move forwardly and upwardly in a short radius, due to the cam surface of the cam lugs sliding upon the arms, resulting in pressing the corrugation for a portion nearest the axis of the bending radius together while an opposite portion of 40 the corrugation is expanded. The corrugating and bending operation following in rapid succession for the required number necessary to produce the desired angle of elbow, which 45 when reached obtains a carriage advance sufficient to bring the carriage into cooperation with the clutch shifting bar tripping member 94 for a clutch control to throw off the power to shaft 8, and an application of 50 the brake and also for tripping the latch bar 59 to release the lock pin 58 from engagement with the tube; whereupon the finished elbow is withdrawn from the carriage with the parts in position for operation upon a 55 second tube.

Having described my invention, I claim:

1. In a machine of the character disclosed, a carriage for intermittently advancing a 60 sheet metal cylindrical tube, means for circumferentially corrugating said tube, and means for bending the tube to an elbow angle successive to the formation of a corrugation, comprising a head member engaged upon the end of the tube, a pair of spaced 65 arms swinging to engage said head member

and move the same in an arc, said arms being swiveled to swing apart for forcing the head member between the arms.

2. In a machine of the character disclosed, a plurality of segmental dies relatively disposed and reciprocating to circumferentially corrugate a sheet metal tube section sustained between the dies, means for feeding the tube section forward, bending means for forming the corrugated tube into an elbow, 70 comprising a pair of arms oscillating as a unit at an angle to the direction of tube section feed, to engage a head member on the end of the tube section to move the same in an arc, said arms being hinged for swinging 80 the same apart for tube and head insertion into the operative portion, means for oscillating said arms in timed relation to the corrugating dies, and said head member detachably secured upon the end of the tube section 85 cooperating with said arms.

3. In a machine of the class described, bending mechanism, a member adapted to be detachably engaged upon the end of a sheet metal pipe section for cooperation with said 90 bending mechanism to bend the pipe section to an elbow angle, comprising an annulus having a pair of diametrically disposed radial cam lugs extending therefrom, a collar secured within said annulus, said annulus and collar arranged to provide a circumferential recess therebetween to receive the end 95 of a pipe section.

4. In a machine of the class described, bending mechanism, a member adapted to be 100 detachably engaged upon the end of a sheet metal pipe section to provide a head for cooperating with said bending mechanism to bend the pipe section to an elbow angle, comprising a plurality of concentrically united annuli and providing an annular recess therebetween open to one end for insertion upon the end of a pipe section, and a pair of radial cam lugs projecting from the outer annulus for engagement with the bending 105 mechanism for moving the head member in an arc and thereby bend the pipe.

5. In a machine of the character disclosed, means for circumferentially corrugating a sheet metal pipe section, a carriage movable from and toward said corrugating means for receiving and advancing the pipe section to said corrugating means having a plurality of different diameter recesses open to one end of the carriage respectively for inserting different diameter sizes of pipe section into the carriage, a pin capable of being projected into a recess to hold the pipe firmly in place, a slide member for alternately depressing or releasing said pin, and means disposed at the fore and aft carriage traversing limits for automatically operating said slide member in alternate stroke motion.

6. In a machine of the character dis- 130

closed, reciprocating dies for circumferentially corrugating a sheet metal pipe section, a mandrel sustained for engagement into the pipe section having an anvil on the end thereof for cooperating with said dies, a reciprocating ratchet bar carried by said mandrel, a carriage translatable upon said mandrel in forward and retreat stroke directions receiving and feeding the pipe section to the corrugating dies, a pawl carried by said carriage adapted to cooperate with said ratchet bar, a latch member movable transversely to the pawl for denormalizing said pawl, and means for automatically actuating said latch member for normalizing said pawl at the end of a retreat stroke of said carriage.

7. In a machine of the character disclosed, means for circumferentially corrugating a sheet metal pipe section, a mandrel sustained for engagement into the pipe section having an anvil on the end thereof for cooperation with said corrugating means, a reciprocating ratchet bar longitudinally slidable upon said mandrel, a carriage translatable upon said mandrel toward and from said corrugating means and having a yielding pawl engageable with said ratchet bar, a rotative cam for reciprocating said ratchet bar, transmission gearing including a clutch for transmitting said rotative cam, and clutch controlling means operative by said

carriage at its fore and aft limits of motion upon said mandrel.

8. In a machine of the class described, means for circumferentially corrugating a sheet metal pipe, a carriage movable in opposite directions for receiving the pipe and feeding the same to said corrugating means, said carriage having an annular recess into which one end of the pipe is engaged, a pin carried by said carriage movable to engage and secure the pipe in its engagement with the carriage, and a slide member mounted in said carriage reciprocable for actuating and releasing said pin.

9. In a machine of the class described, means for circumferentially corrugating a sheet metal pipe, a carriage movable in opposite directions for receiving the pipe and feeding the same to said corrugating means, said carriage having an annular recess into which one end of the pipe is engaged, a pin carried by said carriage movable to engage and secure the pipe in its engagement with the carriage, and a slide member mounted in said carriage reciprocable for actuating and releasing said pin and in a direction lengthwise with the carriage motion for automatic control by independently arresting its motion with the carriage.

In witness whereof, I hereunto subscribe my name.

CHARLES J. HOLUB.
